UNITED STATES PATENT OFFICE.

JESSE H. BUNNELL, OF NEW YORK, N. Y.

TELEGRAPH-SOUNDER.

SPECIFICATION forming part of Letters Patent No. 267,833, dated November 21, 1882.

Application filed October 19, 1882. (No model.)

To all whom it may concern:

Be it known that I, JESSE H. BUNNELL, a citizen of the United States, and a resident of the city, county, and State of New York, have 5 invented certain new and useful Improvements in Telegraphic Sounders, of which the following is a specification.

My invention relates to a certain class of instruments which are employed in the telegraphic service, by means of which the operator interprets the communication transmitted from a distant station by listening to the sounds produced by the to-and-fro vibration of the armature-lever of an electro-magnet between two 15 fixed points or stops.

Hitherto it has been usual to attach the electro-magnetic apparatus and stops rigidly to a board, preferably of hard wood possessing resonant qualities, and to secure such base firmly 20 to the upper surface of a table or shelf, either directly or by means of a stiff metallic base or frame surrounding the base-board of the instrument and rigidly secured thereto, and also to the table. In an apparatus thus mounted 25 the blows of the armature-lever are received upon a metallic sounding-post, and the vibrations of the post are communicated to the base and thence to the table to which it is secured. Thus the table forms, in some sort, a resonator, 30 for re-enforcing and strengthening the sound-vibrations imparted to it by the sounding-post. This construction of the apparatus, however, presents certain objectionable features. The sounds produced are almost entirely dependent 35 upon the character of the table or shelf upon which the apparatus is placed, and in case it is necessary to place the instrument upon a solid surface incapable of being thrown into vibration the sounds produced are not only weak 40 in volume but of a harsh and disagreeable tone. In case the metallic base or frame is employed, it has been usual to clamp the base-board of the instrument thereto by each of its four edges, thereby checking its sonorous vibration, and 45 materially injuring the volume and quality of tone of the instrument. An additional and very serious objection often arises from the circumstance that the vibrations communicated to the supporting-table by the apparatus in the 50 manner hereinbefore described are necessarily imparted to other independent instruments

standing upon the same table, and in the case of delicately-adjusted relays and other like receiving-instruments their normal operation is thereby interfered with.

The object of my invention is to provide a resonator or sounding-board for a telegraphic receiving apparatus of this character, which shall be attached thereto and supported in such a manner as to freely take up the sonorous vibrations produced by the impact of the armature-lever and to re-enforce and strengthen them to the required degree without imparting them to the table or other support upon which the entire apparatus rests.

In the accompanying drawings, Figure 1 is a vertical longitudinal section of an apparatus embodying my invention, and Fig. 2 is an inverted plan of the same.

The operative parts of the sounder which I have represented do not differ from those in ordinary use. They comprise an electro-magnet, M, having a soft-iron armature, m, rigidly secured to a horizontal metallic lever, L, which is pivoted at l to a stationary metallic support, N. When the armature m is attracted by the electro-magnet M the lever L impinges upon a sounding-post, P, which is preferably constructed in the form of a bridge or arch, as shown in the figure. The upward motion of 80 the lever, when released by the demagnetization of the electro-magnet M, is caused by the retractile force of an adjustable spring, S, and is limited by an adjustable stop, H, mounted upon the bracket p, projecting from the sounding post or arch P. The downward excursion of the lever may be adjusted by means of a suitable stop, I. The sounding-post P is firmly secured at its foot to a resonator or sounding-board, B, by means of suitable screws, e e, or other equivalent means. The electro-magnet M is in like manner preferably secured to the sounding-board by means of screws ff. The resonator or sounding-board B (which I prefer to construct in the form of an oblong parallelogram with round corners, as shown in the figure,) may be made of any suitable resonant material, such as hard wood, metal, or glass, the former being generally preferable. The sounding-board B is mounted within and surrounded by a rigid metallic frame, A, which is designed to be rigidly secured to a table or

other convenient support by means of screws passing through suitable apertures, *a a*. Although the metallic frame *A* entirely surrounds the sounding-board *B*, the two are separated 5 from actual contact with each other, except as hereinafter stated, by a narrow space, as shown at *b*. The sounding-board is rigidly clamped or secured to the frame *A* at one of its edges only, leaving its remaining portion 10 free to vibrate in a manner hereinafter to be described. This is effected by means of three projecting supports, *C C C*, upon the inner surface of the frame *A*, to which supports the sounding-board is rigidly secured by means of 15 screws *c c c*. Thus it will be understood that while the oblong sounding-board *B* is rigidly clamped or fastened to the base *A* by one of its shorter edges its remaining portions are left free to take up and re-enforce the vibrations 20 set up by the impingement of the lever *L* upon the sounding-post *P*. The vibrations are, however, confined to the sounding-board, and are not transmitted through the rigid metallic frame *A* to the table beneath. 25

By means of the hereinbefore described organization of parts I am enabled to obtain a clear mellow tone of great strength and volume, the characteristics of which are not perceptibly influenced by the nature of the support 30 upon which the base rests, whether the latter be capable of vibration or not.

In order to prevent any undue flexure of the sounding-board *B*—as, for example, that caused by the accidental placing of some heavy body 35 thereupon—I provide a projection, *d*, upon the inner side of the frame *A* and underneath the free end of the sounding-board, which serves

as a stop and support for the latter in such case.

I claim as my invention—

1. The combination, substantially as herein-before set forth, of an electro-magnet, a movable armature-lever, a stationary sounding post or bridge upon which said lever impinges, a resonator or sounding-board to which said sounding post or bridge is rigidly secured, and a stationary base or support to which said resonator or sounding-board is clamped by one of its edges only, thereby leaving its remaining portion free to take up the vibrations of 50 the sounding-post.

2. The combination, substantially as herein-before set forth, of an electro-magnet, a movable armature-lever, a stationary sounding post or bridge upon which said lever impinges, a resonator or sounding-board to which said sounding-post and electro-magnet are respectively secured, and a stationary base or support to which said resonator or sounding-board is clamped by one of its edges only. 55

3. The combination, substantially as herein-before set forth, of a rigid base or frame surrounding a resonator or sounding-board and clamped thereto by one of its edges only, and a telegraphic sounder mounted upon that portion of said sounding-board which is free to vibrate. 60

In testimony whereof I have hereunto subscribed my name this 10th day of October, A. D. 1882.

JESSE H. BUNNELL.
